UNITED STATES PATENT OFFICE.

JOSEPH EDWARD FARRELL, JR., OF WASHINGTON, DISTRICT OF COLUMBIA.

FIRST-AID KIT.

Application filed November 19, 1920. Serial No. 425,146.

To all whom it may concern:

Be it known that I, JOSEPH EDWARD FARRELL, Jr., a citizen of the United States of America, residing at Washington, in the District of Columbia, have invented certain new and useful Improvements in First-Aid Kits, of which the following is a specification.

My invention relates primarily to a device which provides a hermetically sealed container for various surgical articles and medicinal preparations and other items which are of use in rendering first aid to the wounded or injured.

15 My invention consists of a two-part cup shaped cylindrical vessel which when assembled with the open faces of the cup-shaped casings disposed opposite each other, and locked together in the manner provided, furnish a container which is water proof and air tight while being transported or when it is otherwise not in active use: in other words it is a hermetically sealed container for first aid instrumentalities.

20 25 My invention includes an improved tray which acts as a locking agency for the cup-shaped vessels and provides at the same time a dividing diaphragm between the two cups and the two ends of the tray and I have devised especially in connection with my present improvement a novel bottle stand or spool which insures safety for the bottles and their contents during transportation; and also, when removed from the tray, affords means for easy accessibility of each bottle; this is a great improvement on any heretofore engineered proposition of this nature because it provides, when assembled, an armored container and when disassembled quick access to each vessel and item.

30 35 40 In connection with the foregoing I also provide a reel upon which the tapes, bandages, thread and any similar item can be wound and unwound with great facility and this reel affords also a journal or center, for the bottle stand, or spool, to rotate on, and furthermore it holds the said bottle stand in position when the parts are being assembled; the reel is mounted on a central spindle fixed to the diaphragm aforesaid and affords in turn an axle for the reel to turn on. These and various other improvements I hereinafter describe at length in the body of the specification and 45 50 55 in connection with the accompanying drawings which form part of this specification,

and in which Figure 1 represents a vertical section of my improved first aid kit with the contents in position.

Figure 2 is a view of the tray with the reel in position and with the bottle container removed.

Figure 3 is a perspective view of the bottle container filled with bottles.

Figure 4 shows my improved bracket and is a perspective view thereof.

Figure 5 is a vertical section of a first aid kit with some modifications.

Figure 6 is a detail view of a part of a bottle stand.

Figure 7 is a top view of the bottle stand.

Figure 8 is a perspective view of the bottle stand.

Figure 9 is a perspective view of the first aid kit with the bottle stand removed showing the tape and thread reel.

Referring to these drawings 10 is the upper and 11 the lower section of the casing or envelope of the container of the first aid kit; the tray is shown at 12.

The sections are cup-shaped, and when positioned for assembling are disposed with their open faces towards each other; when they are taken apart and the tray 12 is removed they can be used for serving, or measuring liquids, or for other purposes.

At 13 is a bracket secured by any suitable means, such as the screws 14, to the wall 15; this bracket is adapted to support and hold in place the first aid kit. To effect this I provide a platform 16 cup-shaped having at the bottom a felt or cork receiving plate 17 which serves to cushion and support the kit when positioned in place and arrest vertical vibration. This platform is placed at the outer end of the foot piece 18 secured to the lower part of the upright 13. At 19 is a swinging arm, turning on the pivot 20. 21 shows a spring fastened by the rivet 22 to the upright 13 and bearing at its free end against the lower branch 23 of the arm 19 and pressing outwardly against said branch 23.

At the upper end of the swinging arm 19 is a ring 24 having a rubber cover 25; these parts are engineered so as to bear down on the upper end or top of the first aid kit and hold it down tightly in position; at the same time the kit can be readily removed and replaced as the spring 21 will give sufficiently to permit these operations.

At 26 are legs on which the part 10 can

be supported when it is disassembled from the part 11, and its position reversed, and it is used as a cup or measuring device for liquids. These legs are preferably four in number.

I will now proceed to describe the tray 12, which is inclosed within the sections 10 and 11 and in which the various items of the kit are positioned. This tray, shown with 10 its contents in Figs. 1, 2 and 5 is removable as a whole, and when removed can be supported in a horizontal position in any convenient place.

At 27 and 28 are screws which form locking agencies for the tray, screw 27 being attached to, and extending inwardly from, the bottom of the casing 10; by means of this screw the said casing is adapted to be attached to the tray and when brought home 20 the edge 29 of the casing will be drawn up tightly against the rim 30 of the diaphragm 31. When so positioned, the said casing 10 with the rim 30, will present a hermetically sealed joinder.

25 The screw 28 functions with a complementary screw opening in the lower part of the inside of the casing 11 and by means of this the edge 29 of the casing will be drawn up against the rim 30 of the diaphragm 31. 30 The screw 28^a on the member 11 is a modification of arrangement.

It is to be understood that these screws 27 and 28 constitute absolute locking means for securing the parts, heretofore described, 35 tightly together, a mere friction hold, or any means short of the tight lock, would be insufficient for my purposes as my apparatus is subjected to considerable jarring in transportation; furthermore a tight screw joint 40 lock is necessary in order to draw the parts together to render the structure impervious to outside moisture; also in case of its immersion in water it is absolutely sealed: the parts are drawn together as above explained 45 by the securing and locking agencies at the ends of the kit but the seal is effected upon the perfectly smooth edges and surfaces 29, 30 which when properly constructed and brought full home constitute a hermetical 50 seal and such seal is automatically effected by the locking screws 27, 28 at the ends and not at the meeting edges.

55 The diaphragm 31 is formed integrally with the tray and divides the tray into two zones, one of said zones being utilized for holding implements and the other for holding bottles for medicines: it is provided with integrally formed foot pieces 32 which serves to plant the implement firmly on any 60 suitable supporting stand when either or both of the casings are being unscrewed from the tray.

In the upper, or larger zone, I dispose, as stated, a number of implements, a compartment 65 33 being arranged for safety pins.

Another compartment is shown at 34 for scissors and like articles: at 35 is a dropper; the central section 36 is reserved for fibrous material of different sizes; at the end of the larger zone is a chamber 37 reserved 70 for packages of aspirin and other items.

At 38 and 39 on the larger zone I place sealing sleeves, the sleeve 38 having flanges 40 providing an annular chamber 41 for splints. These sleeves also provide means 75 for maintaining the contents of the larger zone in position, holding them in place when the two part casing is being unscrewed.

The smaller end of the tray member is provided with a spindle 42 which screws at 43 in the diaphragm. It is centrally positioned in respect to the tray and at its outer end it affords means for receiving and securing the screw socket of the member 11. When the part 11 is removed by unscrewing 80 at 28 access can be had to the bottle stand or spool 44. This bottle stand is cylindrical in shape and when removed from the tray can be stood on its bottom rendering the individual bottles 45 easily accessible. A 85 space 46 is provided making the reading of the labels on the bottles very convenient. When the casing 11 is withdrawn by being unscrewed at the screw joint 28 and the bottle stand or spool 44, which is really a 90 rack, is still in position, it can be rotated upon the reel 47 which acts as a drum for the bottle holder to turn on.

At 48 is a cover for the bottle stand; it is secured to the upper surface of the rack in 100 any suitable manner and I have shown it here being held in place by the upper edge 49 of the inner tubular wall 50 of the bottle stand which is spun over the upper surface of the cover 48. This joinder of the cover 105 48 to the bottle stand 44, while retaining the parts together, permits at the same time a rotary movement of the cover on the holder. At 51 is a circular opening in the cover 48: when this opening registers with 110 the top of one of the bottles this particular bottle may be withdrawn but the other bottles are securely held in place by the cover; this feature is of value when the bottle stand is in the act of withdrawal 115 from the reel as it serves to retain the bottles and prevents them from falling out.

I have also provided rubber seats 52 to cushion the bottoms of the bottles, and cork stoppers 53 which serve to cushion the bottles at the upper ends against the cover as well as providing stoppers. When assembled the cover 48 provides a roof for the bottles and said bottles, though having at first a slight longitudinal movement in their pocket are cushioned at both ends and are brought up against both ends when the parts are locked together: vertical pockets 54 are provided in the bottle stand, one for 120 each bottle.

For facilitating the turning of the cover 48 I provide a knob 55 and the diaphragm is suitably dished as shown at 56 to permit free space for the knob 55 when the 5 bottle stand is being rotated in the assembling and disassembling acts. The cover 48 is slightly tipped up from the center where it is attached at 49 towards the edge or periphery at 57 and at this latter point 10 the said cover is brought up against the edge 58 of the diaphragm 31. As the member 11 is screwed on to the tray the surface 59 of the bottle stand will be caught by friction in, and by, the complementary 15 concave inner face of the casing 11 and the said casing and the bottle stand will be carried along together and the cover 48 of the bottle stand will be forced by the bottle corks up against the rim 58: this 20 operation effects a tight lock.

The combination of parts as I have engineered them, enables me to secure a very efficient closure; in other words, by reason of the fact that the rotating cylindrical 25 bottle stand, resting in the concave part of small casing 11 at 59 and traveling with it when the two casings are being assembled, permits, and in fact enforces, a much closer fit by reason of the fact that where foreign 30 bodies might intervene between an immovable tray structure, and prevent a hermetical sealing, the bottle holder section 44 of the tray structure as I have built it, is rotated with the cover section of the device during the assembly thereof, and takes up against the diaphragm joint only after the cover seal has been effected, thus insuring a hermetically sealed joint, effective 35 upon the ordinary closure of parts.

40 The reel 47 is mounted upon the spindle 42 and is secured by cotter pin 60. Spools 61 containing thread, tape, and narrow bandages are positioned thereon and such materials can be wound or unwound, as 45 occasion requires while the reel is turning on the spindle.

At 62 is a circular channel in the bottom of the bottle stand 44 and it is in this channel that the ring shaped rubber piece 50 or band forming the cushioning seats 52 is seated.

In Figure 1 is shown a capsule 63 in which needles may be stored.

Having thus described my invention the following is what I claim as new and useful therein and desire to secure by Letters Patent.

1. A first aid kit having an enclosed tray embodying a diaphragm, casings with means for locking same up against the diaphragm and a bottle stand having a cover arranged to be pressed against the diaphragm.

2. A first aid kit embodying two enclosing casings, an enclosed tray, a rotating bottle stand in the tray, and friction means for rotating the stand by means of one of the casings.

3. A first aid kit having enclosing casings, a tray, a revolving bottle stand having a cover, means for turning the latter, and a diaphragm on the tray suitably dished for receiving said cover turning means.

4. A first aid kit embodying an enclosed surgical and medicine holder with a withdrawable bottle rack having individual bottle pockets, and an adjustable top for the rack permitting only one bottle to be removed at a time.

5. In a first aid kit a plurality of cup-shaped casings, a tray providing means for locking said casings together, said tray having a spindle providing a reel mount and means for locking one of the cup shaped casings to said reel mount.

6. A first aid kit having cup shaped enclosing members, an enclosed tray having a reel supporting spindle, the said spindle affording means for supporting a plurality of withdrawable reels.

7. A first aid kit having enclosing vessels, means for sealing them at their open and meeting faces, a tray having a diaphragm dividing it into two parts, a centrally positioned spindle on the diaphragm, a reel providing a drum arranged on the spindle and a revolving bottle spool on the drum.

8. A first aid kit embodying cup shaped and hermetically sealed enclosing vessels, an enclosed tray, a spindle thereon, a revolving spool reel thereon, said reel providing also a drum, and a revolving cylindrical bottle stand on the drum.

JOSEPH EDWARD FARRELL, Jr.
